(57) **CLAIM**

The ornamental design for a cork screw with bottle opener, as
shown and described.

DESCRIPTION

FIG. 1 is a front view of the cork screw with bottle opener;
FIG. 2 is a front view of the bottle opener portion of the cork
screw with bottle opener;
FIG. 3 is a rear view of the bottle opener portion of the cork
screw with bottle opener;
FIG. 4 is a top plan view of the bottle opener portion of the
cork screw with bottle opener;
FIG. 5 is a bottom plan view of the bottle opener portion of the
cork screw with bottle opener;
FIG. 6 is a left-front-bottom perspective view of the bottle
opener portion of the cork screw with bottle opener;
FIG. 7 is a right-rear-top perspective view of the bottle opener
portion of the cork screw with bottle opener;
FIG. 8 is a cross-sectional view of the bottle opener portion of
the cork screw with bottle opener, taken along line 8-8 of FIG.
4;

FIG. 9 is a cross-sectional view of the bottle opener portion of
the cork screw with bottle opener, taken along line 9-9 of FIG.
3;

FIG. 10 is a side view of the corkscrew portion of the cork
screw with bottle opener; and,

FIG. 11 is a side-top perspective view of the corkscrew portion
of the cork screw with bottle opener.

The broken lines in the drawings illustrate portions of the cork
screw with bottle opener and form no part of the claimed
design.
